CLAIM

The ornamental design for a robot, as shown and described.

DESCRIPTION

FIG. 1 is a top-right perspective view of a robot showing our new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof;

FIG. 8 is a back-left perspective view thereof; and,

FIG. 9 is a front-left perspective view thereof.

The broken lines in FIGS. 1-9 depict portions of the robot that form no part of the claimed design.
